HENDERSON P. CHILDRESS, OF MEMPHIS, TENNESSEE.

BALE-BUCKLE.

1,240,672.

Specification of Letters Patent. Patented Sept. 18, 1917.

Application filed May 20, 1916. Serial No. 98,902.

To all whom it may concern:

Be it known that I, HENDERSON P. CHILDRESS, a citizen of the United States, residing at Memphis, in the county of Shelby and State of Tennessee, have invented a new and useful Bale-Buckle, of which the following is a specification.

This invention has reference to bale buckles and its object is to provide a bale buckle having an interlocking entering end with the interlocking portions situated to be embraced or inclosed by the corresponding loop of the bale band and in conjunction with such interlocking portions there is provided a non-rendering extension engaging the loop of the bale band inclosing the interlocking members, whereby any tendency of such loop of the bale band to pull out from the buckle, or render, as such pulling out is known, is obviated.

In accordance with the present invention the buckle is a one piece wire structure suitably bent to form an end bar, two side bars, and another end bar formed by overlapping extensions of the side bars, each terminating in angle prolongations or hooks, one of which is further extended into a side extension and return portion suitably spaced apart in a direction corresponding to the length of the buckle so as to engage and underride the tucked-in end of the applied loop of the bale band on the bale side thereof, whereby the tucked-in end is brought into such strong frictional engagement with the other portion of the bale band loop that rendering is practically obviated.

The invention will be best understood from a consideration of the following detailed description, taken in connection with the accompanying drawings forming part of this specification, with the further understanding that while the drawings show a practical form of the invention, the latter is not confined to any strict conformity with the showing of the drawings, but may be changed and modified so long as such changes and modifications come within the scope of the appended claims.

In the drawings:—

Figure 1 is an elevation of the non-rendering interlocking bale buckle with the bale band applied and shown in section, but with the parts in the initial position; that is, before the bale is released from the press.

Fig. 2 is an end elevation of the structure

of Fig. 1 as viewed from the left hand side thereof.

Fig. 3 is a view similar to Fig. 2 but omitting the bale band and showing the position of the parts when the buckle is subjected to expansive forces occurring when applied to a bale and the latter is released from the compress.

Fig. 4 is a section on the line 4—4 of Fig. 1 with the bale band omitted.

Fig. 5 is a view similar to Fig. 1 but with the buckle pulled; that is, with the parts in position due to the expansive force of the bale exerted upon the buckle.

Fig. 6 is an elevation of the buckle with the bale band in section, showing a step in the application of the second loop of the bale band to the buckle.

In the drawings the buckle is shown as of a one-piece wire construction, it being understood that the wire is of suitable gage, but because of the peculiar construction of the buckle there is no liability of any parts of the buckle pulling apart or pulling out, and therefore the gage of the wire need only be large enough to resist extension of the material of the buckle under the expansive force of the bale.

The buckle of the present invention in so far as the interlocking parts are concerned is shown, described and claimed in another application for a bale buckle filed by me on even date herewith, and consequently no claims are made herein to the interlocking features *per se*, but only to the combined interlocking and non-rendering features of the buckle.

In accordance with the present invention the buckle comprises an end bar 1 designed to receive an end loop 2 of a bale band, such loop being customarily applied at the bench, and when the bale band and buckle are applied to a bale in the compress and reduced to the desired size, the buckle usually hangs pendent so that the end bar 1 may be considered as the upper end bar. The buckle also comprises side bars 3, 4, respectively, each having at the lower end an extension 5, 6, respectively. The extensions are of a length to overlap so that each extension is prolonged beyond the corresponding end of the other extension toward the side bar from which said other extension proceeds. The extension 5 terminates in a hook 7, so termed because as will hereinafter appear it serves the purpose of a hook in conjunction with another hook 8

formed on the outer end of the extension 6. The hooks 7 and 8 are together located about midway of the width of the buckle so as to be inclosed or imprisoned in or embraced by the other end loop 9 of the bale band which engages about the extensions 5 and 6, so that these extensions constitute the other or lower end bar of the buckle. The hooks 7 and 8 are suitably bent with relation to the extensions 5 and 6 to be located exterior to the body of the buckle, being directed away from the extensions 5 and 6 on the sides thereof remote from the end bar 1. The hooks 7 and 8 are further bent so that what 15 may be termed their extremities are closer together than are the throats 10, 11 of these hooks, that is, those portions of the hooks where joining the extensions 5 and 6. Furthermore, the hooks are bent toward each 20 other in the direction of the line of separation of the extensions 5 and 6 one from the other, but the hooks in the initial position of the parts of the buckle, as well as the extensions 5 and 6, are always sufficiently separated to provide an entering end to the 25 buckle through which the loop 9 of the bale band may be threaded.

The hook 7 does not end like the hook 8, but is continued in the form of a side extension 12 which may be approximately in the 30 general intermediate plane of the body of the buckle; that is, a plane extending lengthwise of the end bar 1. The extension 12 terminates in an angle prolongation 13 approximately at right angles to the extension 12 and substantially or nearly parallel with a prolongation of the side bar 3. At the 35 end of the angle prolongation 13 remote from the side extension 12 there is a further prolongation in the form of a return member 14 extending toward a line representing a prolongation of the side 4 and long enough to extend across the loop line of the bale band when applied to the buckle.

40 When the loop 9 is applied to the buckle or carried by the loop 2 and with the band encircling the compressed bale, the loop 9 is threaded on to the extension 6 and hook 8 until within the body of the buckle and beyond the hook end 7 of the extension 5. The 45 buckle has to be swung to one side upon the loop 2 to permit its manipulation, and then is swung back again so that the hook 7 and prolongation 5 move into the loop 9, while the tucked end of the latter is so directed 50 that the return member 14 constituting a part of the non-rendering end of the buckle enters behind the loop 9 and its tucked-in end, that is, it passes on that side of the loop 55 9 toward the bale.

Now, the hooks 7 and 8 and the extensions 5 and 6 are within the loop 9 with the return portion 14 back of the loop. With the parts thus located the bale is released from the 60 compress, whereupon the expansive force of

the bale is exerted upon the loop 9 tending to draw it away from the loop 2. The first effect is to squeeze or compress the hooks 7 and 8 toward each other, this being the direction of least resistance, and the extensions 5 and 6 are therefore brought into side engagement, with the hooks overlapping in a direction perpendicular to the mid plane of the body of the buckle. The next effect of the expansive force of the bale, which force 70 can no longer be exerted to compress the hooks and extensions 5 and 6 toward each other, is resolved into a force tending to pull the extensions 5 and 6 away from the end bar 1. The result of this is that the 75 hooks 7 and 8 have those ends remote from the extensions 5 and 6 moved into engagement and as these hooks already have been brought into overlapping engagement, their throats 10 and 11 meet and the 80 hooks mutually become engaged one with the other. The expansive force of the bale being resisted by the refusal of the buckle to further yield then holds the two legs of the loop 9 in firm compressive engagement 85 with the entering end of the buckle effectively locking the hooks against any tendency to spring apart while the hooks themselves being in close engagement at their throats 10 and 11 effectively resist any tendency 90 to spread the buckle or to pull the extensions 5 and 6 away from the end bar 1.

In the meantime the tucked-in end of the loop 9 is turned rather sharply about the return member 14 constituting the non-rendering member of the buckle, so that the tucked-in end of the loop 9 is forced against the outer leg of the loop 9 so strongly that the friction thus produced effectively overcomes any tendency of the loop 9 to render. 100

There is therefore provided a buckle which when applied to the bale will not yield to any force short of a force destructive to the material from which the buckle is made and, moreover, the bale band cannot under the exertion of any force of which the bale is capable be caused to render. 110

The interlocking entering end of the buckle is entirely inclosed by the loop 9 of the bale band constituting the bale applied end of the band and the bulge caused by the overlapping hooks contributes to the non-rendering feature of the buckle by more or less indenting or crimping the particular portion of the band engaged by it without, 115 however, tending in any way to tear the band.

In order to prevent the tucked-in end of the loop 9 of the bale band from tending to force the hook 8 from its interlocking engagement with the hook 7, the extreme end of the hook 8 is beveled, as shown at 120 15, so as to avoid any material engagement of the tucked-in end of the loop 9 with such hook 8. 130

Because of the intimate mutual interlocking of the hooks 7 and 8 and the confining of these hooks in the locked position by the applied loop 9 of the bale band, the gage of the wire employed may be much less than that which would be necessary to prevent drawing out of the entering end of the buckle in the absence of the interlocking hooks 7 and 8. Since bale bands 5 are sold by the pound this means that many more buckles are supplied to the pound when said buckles are made in accordance with the present invention than would be the case with a buckle depending solely upon the resistance of the material to forces tending 10 to bend it.

What is claimed is:—

1. A one-piece wire bale buckle, comprising an end bar, two side bars and respective 20 extensions of the side bars overlapping to form another end bar remote from the first end bar, both extensions having their extremities formed into hooks exterior to the buckle and on the side of the entering end 25 of the buckle remote from the first-named end bar, one of the hooks having a prolongation in the form of a side extension and a return thereof in spaced relation to said side extension on the side of the latter remote 30 from the body of the buckle to constitute a non-rendering member to engage the looped end of a bale band applied to the entering end of the buckle.

2. A one-piece wire bale buckle having 35 end and side bars, one end bar comprising the entering end of the buckle and formed by overlapping extensions of the respective side bars with one extension terminating in a hook and the other extension being provided with a hook, said hooks being spaced 40 apart in the direction of the width of the buckle and the ends of the hooks remote

from the respective extensions approaching so as to engage and mutually interlock under the pull of the bale band, and the second-named hook having a prolongation in 45 a direction cross-wise of the applied loop of the bale band and constituting a non-rendering member engaging that loop of the bale band applied to the entering end bar 50 of the buckle.

3. A one-piece wire bale buckle having end and side bars, one end bar comprising the entering end of the buckle and formed by overlapping extensions of the respective 55 side bars, one extension terminating in a hook and the other extension being provided with a hook, said hooks being bent away from the entering end of the buckle on the side thereof remote from the other 60 end bar and spaced apart in the direction of the width of the buckle and at the ends remote from the extensions approaching toward each other so as to mutually interlock under the pull of the bale band, the second-named hook having a prolongation extending 65 in a direction cross-wise of that loop of the bale band applied to the entering end of the buckle and having a return portion also extending cross-wise of the applied 70 loop of the bale band and bent with relation to the plane of the body of the buckle and of the extension carrying it to lie on the bale side of the applied loop, whereby said return portion constitutes a non-rendering 75 member for the buckle.

In testimony, that I claim the foregoing as my own, I have hereto affixed my signature in the presence of two witnesses.
